UNITED STATES PATENT OFFICE.

JOSEPH LUCVETT BOWLES, JR., OF PITTSBURGH, PENNSYLVANIA.

EFFICIENCY AND EDUCATIONAL CHART.

1,419,809.

Specification of Letters Patent. Patented June 13, 1922.

Application filed July 11, 1921. Serial No. 483,737.

To all whom it may concern:

Be it known that I, JOSEPH L. BOWLES, Jr., a citizen of the United States, residing at Pittsburgh, in the county of Allegheny and State of Pennsylvania, have invented certain new and useful Improvements in Efficiency and Educational Charts; and I do hereby declare the following to be a full, clear, and exact description of the invention, 10 such as will enable others skilled in the art to which it appertains to make and use the same.

This invention relates to a system of and means for keeping tab on one's own personal, social or business conduct, and particularly to a chart used for self-analysis, or to enable a person to keep a daily record or account of his own conduct and dealings with his fellowmen, thus revealing his strong 15 and his weak points and enabling him to tell just where he stands with himself at the end of the day.

The invention consists of a chart specially designed and adapted to enable the user to 25 keep an accurate account of his or her personal, social or business conduct, or in other words, to take a daily inventory of himself that will bring to mind at the close of the day the fact whether the trend of his life 30 is toward success or failure, with the ultimate object of bettering his condition, not only morally, spiritually or physically, but along commercial lines.

All individuals are being constantly 35 swayed by human emotions—at one time a positive thought will influence; at another a negative thought will dominate one's actions. The degree to which one is able to control the character of his thoughts and 40 acts determines both the quality and quantity of his success. If positive (or constructive) thoughts dominate one's life, he is traveling the road to success. The reverse is true if he permits the negative (or destructive) side of his nature to dictate his course. 45 As men and women are able to control their thoughts and acts, they may live successful, well-rounded lives, or the reverse.

The reading of good literature is inspiring. 50 To read the histories of great and successful men is an inspiration, for such works or biographies are replete with thoughts and acts that spur one onward and upward. The shortcoming of the individually usually is 55 that he does not capitalize the inspirational value of what he reads. Being human, he is

prone to forget, and when in need of the helpful suggestions found in books or other literature, he does not know just where to find them. While in no sense a substitute 60 for good reading my improved charts, nevertheless contain the sum total of the inspiring thoughts which good reading and experience create. They are quite simple in form, and at the end of the work day or just before 65 retiring, one may in the space of only a few minutes check up with himself and tell just where he stands, and whether he has been a failure or a success that day, and why. 70

Many men are not successful in business because they do not accurately analyze themselves. All know and admit that there is a cause for every effect. The difficulty lies in the fact that there are so many who rush 75 through life without introspection or self-analysis. They cannot see that they are failures or are headed in that direction until perhaps it is too late to turn back. They are so absorbed in their business—so close to 80 their jobs and in such a hurry at all times that they do not see things in perspective as all must if they are to rise above the multitude. They do not evaluate accurately.

How many men stop long enough to analyze themselves, in order to determine why they are neither failures nor successes? How many men really think? The answer is to be found in the comparatively small number of men who, gauged by the world's measure, 90 are looked upon as successful business men. My improved charts compel one to think. Then, if there be innate ambition, impel one to go forward.

These charts are reminders of what one 95 must do to succeed. They operate upon the theory that the doors to success are opened with two keys; one to open the door to desire; the other the door to truth. These charts will point the way. It is for the user 100 to enter. To one who has no desire to succeed, the chart will be of little value. On the other hand, if one is not going to be frank with himself in telling the truth about himself, his ambition may be guided erroneously, for the charts when truthfully kept will reveal both his weak points and his strong points. If he is not frank in checking up with himself, he will be fooling no one but himself, for these charts are his own 110 private property and the eyes of no other person may see them unless he shall so

choose. The user should therefore not be hypercritical or hypocritical. Simply be frank—and then face the facts.

The accompanying drawing represents a plan view of a chart embodying my invention in the form used for keeping tab on one's business conduct. Similar charts with different words or phrases depicting various shades of character and temperament, or indicative of thought or action along the lines of one's personal and social conduct, may be used, embodying the same principle as the form shown. As shown, the chart comprises a sheet A of paper or the like, similar to the leaves of a book, or a folder, any desired number of which may be bound or fastened together in pamphlet form.

On the left-hand side or margin of each leaf or page there is a vertical column, which is preferably divided into several panels a , a^1 and a^2 , and has written or printed thereon a series of words or phrases selected for a self-analysis of one's business conduct, each leaf being ruled with vertical and transverse lines which extend nearly the full length and width thereof, so as to provide a vertical series of spaces equal to the number of days in a month and a horizontal series of spaces equal to the number of words or phrases used to depict the various shades of character, etc., or to indicate thought or action along various lines, each word or phrase being arranged directly opposite one of the series of horizontal spaces and the vertical series of spaces being numbered consecutively from 1 to 31 to indicate the days of the month. At the top of the column on the left-hand page or leaf is placed the word "Positive", and at the top of the column on the right-hand page or leaf the word "Negative", the positive side being designed to quiz one's self as to matters, acts or deeds of a desirable character, and the negative side to quiz one's self as to matters, acts or deeds of an undesirable character. Below each column, directly opposite or in alinement with a horizontal series of spaces a^3 corresponding with the superposed spaces numbered to denote the days of the month, are the words "Percent perfect each day" and below the latter the words "Average for month", opposite a space at the foot of the column, and in the upper right hand corner is written "% Perfect" over a vertical series of spaces a^4 alined with the horizontal series, so that in checking up day by day one's business conduct a space is provided for each item for each day in the month and also a space for summarizing the per cent perfect for each day of the month, and the average per cent for the entire month, also the average for each item each day in the month. As stated, the charts for recording matters, acts and deeds relating to personal or social conduct

are the same as that for business conduct, except a difference in words and phrases used.

To grade one's self one may use the following key: X to denote zero; 1 to equal $1/4$ 70 or 25%; 2 to equal $2/4$ or 50%; 3 to equal $3/4$ or 75% and 4 to equal $4/4$ or 100%, or perfect mark. Add the percentages at the end of the day and divide by the number of items to get the per cent perfect for 75 the day. For instance, assuming that the positive side of the chart contains 55 items, and that one has graded himself 100% on 5 of the items, 75% on 15 items, 50% on 20 items, 25% on 10 items and zero on the remaining 5. This gives a total of 2975%, which, divided by 55 gives an average for the day of 52%. In other words, for that day the person would be only 52% perfect, which is very low. Perfect would be 80 5500% and, divided by the number of items, (55) would give 100%, which is the desired goal. The negative side of the chart is graded in the same manner. Assuming that there are 26 items on the negative side, and that one's grading on the negative side averages 60%, then the joint average may be ascertained by adding the positive average of 52% and the negative average of 60% and dividing by 2, or 56% perfect for the 85 day. At the end of the month, compute the percentages on each item, separately on the positive and negative sides, for each day and divide by the number of days in that month placing the result in the "% Perfect" 90 column of spaces a^5 on the extreme right. Then total the percentages in this column, dividing the result by the number of items, and that will give the average for the 95 month. Both positive and negative sides 100 of the chart are to be figured up in this manner, the two results added, and then divided by 2 to get the joint average for the month. If the result shows an upward tendency it 105 will indicate that the user is progressing, whereas if it shows a downward tendency it will indicate that the user is going backward.

The average is arrived at by dividing the total joint averages for the month by the 115 number of days in that month. For instance, assuming that for 10 days in the month the user had a joint average of 70%, 5 days 75%, 10 days 80% and 5 days 90%. This would give a total of 2325%, which, divided by a 30 day month, would make the average for that month 77%, indicating that the user's record is improving.

At the end of the first and each succeeding month, on figuring up one's averages on 125 each item, the user will see just where his weak points and his strong points lie, and will know where to work for improvement.

While the described chart is specially designed to be used by business men, or men 130

of affairs generally, my invention is not limited in its application to such uses, but by a mere change of words and phrases to suit the particular use to which it is to be put, it may be used for the betterment of individuals in every walk of life, and particularly in public schools, Sunday schools and colleges.

Having thus described my invention, what I claim as new and desire to secure by Letters Patent of the United States is:

1. A chart of the character described, comprising a sheet of suitable material having the surface thereof ruled with vertical and horizontal lines so as to form a series of spaces at one side of the sheet in both vertical and horizontal alinement, and a vertical column at the other side of the sheet having written or printed therein a series of words and phrases depicting various shades of character and temperament, or indicative of thought or action along the lines of business, personal or social conduct, and in alinement successively with said horizontally alined spaces; said vertical series of spaces being numbered consecutively to correspond with the number of days in a given period of time, delineated spaces below and in alinement with said vertical series of spaces, and words or phrases in alinement with said delineated spaces indicating percentages and the average for the number of days covered by said period of time.
2. A chart of the character described, comprising two sheets of suitable material having the surface of each sheet ruled with vertical and horizontal lines so as to form a series of spaces at one side of the sheet in alinement both vertically and horizontally, and a vertical column at the other side of the sheet having written or printed therein a series of words and phrases depicting various shades of character and temperament, or indicative of thought or action along the lines of business, personal or social conduct, said words and phrases being in alinement successively with said horizontal series of spaces, those on one sheet being of a positive and those on the other sheet of a negative character; said vertical series of spaces on each sheet being numbered consecutively to correspond with the number of days in a given period of time, delineated spaces below and in alinement with said vertical series of spaces, and words or phrases in alinement with said delineated spaces indicating percentages and the average for the number of days covered by said period of time.

In testimony whereof I affix my signature in the presence of two witnesses.

JOSEPH LUCVETT BOWLES, Jr.
